UNITED STATES PATENT OFFICE.

CHARLES DE LUKACSEVICS, OF NEW YORK, N. Y., ASSIGNOR TO ANDREW GROSS, OF NEW YORK, N. Y.

CARBURETER.

1,244,712.

Specification of Letters Patent. Patented Oct. 30, 1917.

Application filed June 24, 1916. Serial No. 105,703.

To all whom it may concern:

Be it known that I, CHARLES DE LUKACSEVICS, a citizen of the United States, residing at New York, in the county of New York 5 and State of New York, have invented new and useful Improvements in Carbureters, of which the following is a specification.

This invention relates to improvements in carbureters for internal combustion engines 10 and to a carbureter of that type wherein a distributing element of felt or equivalent material is employed to effect the transfer of gasolene from the fuel chamber of the carbureter to the mixing chamber.

15 The invention consists more particularly in improvements in the construction and relation of the valves which control the delivery of air and gasolene to the mixing chambers and motor suction tube, in the relation of 20 these valves to one another whereby their operations are correlated and in the construction of the mixing chambers and their relation to one another and to said valves, the objects served being an exact regulation 25 of the quantum and proportions of the fuel mixture with regard to any speed in the normal range of the engine, certainty and simplicity in the operations of the valves, a thorough mixing of the air and gas, and the 30 elimination of any necessity for adjustments. The invention also consists in certain detail features of structure, combination and relation which will appear as the description proceeds.

35 An embodiment of the invention is illustrated in the accompanying drawings, where- in:

Figure 1 is a plan view of a carbureter in which the features of the invention are 40 incorporated, with parts shown in section;

Fig. 2 is a central longitudinal sectional view thereof;

Fig. 3 is a horizontal sectional view on the line 3—3 of Fig. 2;

45 Fig. 4 is a detail plan and Fig. 5 is a detail elevation, partly in section, of the valve which controls the gasolene vapor given off by the distributing element;

Fig. 6 is a detail plan and Fig. 7 is a detail 50 elevation, partly in section, of the valve which controls the admission of the air and gasolene vapor to the inner mixing chamber;

Fig. 8 is a detail plan and Fig. 9 is a detail section of an operative connection between the valves shown in Figs. 4 and 6; 55 and

Fig. 10 is a detail plan and Fig. 11 is a detail elevation, partly in section, of a sleeve which co-acts with the valve shown in Figs. 6 and 7. 60

Similar characters of reference designate corresponding parts throughout the several views.

The carbureter includes a fuel chamber 1 and an air passage 2. The fuel chamber is 65 preferably of the float feed type and it is provided with float feed mechanism 3 of any suitable or desired construction. The air passage 2 is defined by an annular wall 4 which projects through the fuel chamber 70 at one side thereof and at its lower end extends from an air inlet pipe 5 preferably provided with an adjustable regulating valve 6. The wall 4 at its upper end opens into an outer mixing chamber 7 which is 75 arranged in concentric surrounding relation to an inner mixing chamber 8 in direct or open communication with the motor suction tube (not shown).

An annular horizontal shoulder is ar- 80 ranged between the upper end of the wall 4 and the lower end of the outer wall 10 of the mixing chamber 7. The felt distributing element 11 is in the form of a ring and closely surrounds the wall 4 within the fuel 85 chamber. The element 11 is completely submerged in the fuel in the chamber 1 and is confined against the under side of the shoulder 9 which is provided with openings 12 through which gasolene is given off from 90 the element 11 into the mixing chamber 7.

The openings 12 are preferably arranged in groups along arcs of a common circle and are controlled by a valve 13 which is preferably of the construction shown in Figs. 95 4 and 5. As shown, this valve consists of a ring having an L-shaped cross-section whereby it may fit snugly in the angle formed by the shoulder 9 and the wall 10; and the horizontal portion of the valve is provided with 100 curved slots 14. The number and outline of the slots 14 correspond to the number of groups of openings 12 and to the arrangement of these groups along a common circle.

When the valve 13 is fully open the openings 12 are completely disclosed or uncovered through the slots 14, and when the valve 13 is closed, the openings 12 are either entirely covered or else a single opening of each group may be allowed to remain uncovered to enable the engine to be run at a minimum or throttling speed, as is well known in the art.

The communication of the air passage 2 with the inlet pipe 5 is controlled by a disk valve 15 which seats against the wall of an opening 16 formed in a flange 17 at the lower end of the passage 2. The valve 15 is slidably mounted upon a stem 18 and is urged toward its seat by a spiral spring 19 surrounding said stem and bearing against said valve and against a collar 20 at the upper end of said stem. In order that the tension of the spring 19 may be regulated as desired, the stem 18 has its lower end threaded and provided with an adjusting nut 21 which is centered in a recess formed externally of the pipe 5 at the base or under side of the carburetor. Obviously, with this arrangement, the spring 19 holds the stem elevated as far as permitted by the nut 21 and by turning said nut said stem may be lowered or raised to cause the spring to bear with greater or less pressure, as desired, on the valve 15.

In the normal running of the engine, the air which is admitted by the valve 15 through the opening 16 passes upward through the passage 2 and enters the mixing chamber 7, wherein it takes up gasoline from the felt distributing element 11 and forms a somewhat intimate mixture therewith. The mixture thus formed in the chamber 7 passes into the inner mixing chamber 8 and from thence to the motor suction tube.

The inner wall of the chamber 7 and at the same time the single annular wall of the chamber 8 is provided by a valve organization which consists of a generally cylindrical valve body 22 and a stationary sleeve 23 which surrounds and co-acts with the valve body 22. The sleeve 23 is provided with upper and lower external and internal shoulders 24 and 25 which are utilized for the support of the valve body 22. The shoulder 24 is incident to the provision of a flange 26 which circumscribes the upper end of the sleeve 23 and by means of which said sleeve is supported within the carburetor casing. The cylindrical valve body 22 is provided with upper and lower external shoulders 27 and 28 which overhang and bear against the shoulders 24 and 25. The shoulder 27 is incident to the provision of a flange 29 which circumscribes the upper end of the valve body 22 and fits snugly and with sealing effect in an annular recess formed in the carburetor casing. Within the outer wall of

this recess a slot 30 is provided through which an operating arm 31 secured in the flange 29 projects, this arm being used to effect a rotation of the valve body 22 about its axial center.

The cylindrical portion of the valve body 22 is provided with relatively large slots 32 and the sleeve 23 is provided with similar slots, similarly arranged, 33. The quantum of the mixture delivered to the motor suction tube is greater or less as the registry of the slots 32 and 33 is more or less complete. Figs. 2 and 3 show these slots in full registry and it follows that a maximum quantum of fuel mixture will be delivered to the motor suction tube. Obviously, by rotating the valve body 22 whereby the slots 32 will be brought partly out of registry with the slots 33, the quantum of the mixture delivered to the motor suction tube will be proportionately decreased; and if the valve body 22 be rotated until the slots 32 are nearly but not quite wholly out of registry with the slots 33 so that the communication of the outer and inner mixing chambers 7 and 8 is reduced to a minimum, the supply of fuel to the motor suction tube will be only sufficient for the running of the engine at low or throttling speed.

The valve body 22 is provided below the slots 32 with a horizontal base 34 and below the base 34 with an air chamber 35 whose wall is of generally spherical outline and serves the further function of deflecting the air that issues from the passage 2 over the openings 12 of the shoulder 9 whereby the intimate mixture of air and gasoline vapor within the chamber 7 will be promoted. The wall of the air chamber 35 is provided with air inlet openings 36 and the base 34 is provided with air passages 37. The object of the chamber 35, with the openings 36 and the passages 37, is to provide for an augmented supply of mixture when the engine is running at high speed. Normally, however, this augmented supply of air is not required; and accordingly a disk valve 38 working with relation to a seat 39 above, and from which the passages 37 extend, normally cuts off the communication of said passages with the space above the base 34. The valve 38 is mounted on an axially located stem 40 which, in the present embodiment, is axially and vertically slidable and raises or lowers the valve 38 in its sliding movement. The valve 38 is urged toward its seat by a spiral spring 41 surrounding the stem 40 below the base 34 and bearing at its upper end against said base and at its lower end against a collar or enlargement 42 at the lower end of the stem 40. As a matter of convenience, the wall of the air chamber 35 has a centrally located sleeve 43 which closely surrounds the collar 42 of the stem 40 and an extension of the collar 130

20 on the stem 18 of the valve 15, thereby serving as a retainer and guide for the stem 40 and as a retainer for the stem 18.

In order to increase the intimacy of the 5 constituents of the fuel mixture a fan-like element 44, for convenience termed a fan, is preferably arranged within the chamber 8; and in the embodiment disclosed the hub of this element is fitted upon the upper portion 10 of the stem 40 between the valve 38 and a retaining nut at the upper end of said stem. The gaseous mixture which is admitted into the chamber 8 acts on the fan 44, rotating the latter, and by virtue of the resistance 15 offered by the friction of the fan bearings is caused to rise in a whirling column through said chamber and through the motor suction tube.

The operation of the valve 13 is incident 20 to an adjustment of the valve body 22 and is for the purpose of maintaining a correct proportioning of the constituents of the fuel mixture for any quantum that may be delivered to the motor suction tube. To effect 25 the operation of the valve 13 from the valve body 22, a connection is employed which is preferably of the construction shown and consists of a flat cross-shaped spring member or spider 45 whose arms are bifurcated 30 to fit over radial ribs 46 arranged at suitable intervals on the valve 13 and whose hub is provided with radial recesses 47 to fit over radial ribs 48 at the lower end of the valve body 22, specifically, at the junction of the 35 wall of the air chamber 35 with the sleeve 43. The spring spider 45, when assembled in this manner, is subjected to downward force whereby it will hold the valve 13 firmly on the angular seat provided therefor 40 by the shoulder 9 and the wall 10; and said spring will obviously transmit the rotation of the valve body 22 to the valve 13 whereby the latter will reduce or increase the exposure of the openings 12 through the slots 14 45 in accordance with adjustments of the valve body 22 to reduce or increase the registry of the slots 32 and 33.

The carbureter, viewed externally, may be 50 of any desired form and is provided with the usual attachment flange 49. In the embodiment disclosed, the mixing chamber 8 is continued through this flange.

I claim—

1. In a carbureter for internal combustion 55 engines, in combination, an air passage, a fuel chamber, an annular wall separating said passage and chamber and having an annular horizontal shoulder at its upper end, said shoulder having openings extending between its upper and lower faces, an absorbent 60 distributing element surrounding said annular wall within the fuel chamber and extending to said shoulder, said shoulder overhanging said element, a mixing chamber 65 above said air passage and into which the

latter opens, and an annular valve rotatably mounted on said shoulder and having slots through which said openings may be disclosed.

2. In a carbureter for internal combustion 70 engines, in combination, an air passage, a fuel chamber, an annular wall separating said passage and chamber and having an annular horizontal shoulder at its upper end, said shoulder having openings extending 75 between its upper and lower faces, an absorbent distributing element surrounding said annular wall within the fuel chamber and extending to said shoulder, said shoulder overhanging said element, a mixing 80 chamber above the air passage and into which the latter opens, the mixing chamber having an annular wall which forms an angle with the shoulder, and an annular valve of angular cross section rotatably 85 mounted on the shoulder and in the angle formed by the shoulder and the annular wall of the mixing chamber, said valve having slots through which said openings may be disclosed.

3. In a carbureter for internal combustion 90 engines, in combination, inner and outer concentric mixing chambers, an air passage communicating with the outer chamber, a fuel chamber, an absorbent distributing element submerged in the fuel in the fuel chamber, the wall separating said fuel chamber and outer mixing chamber having openings between said chambers through which gasolene may be given off by the distributing element into said outer mixing chamber, an annular rotatable valve controlling 95 said openings, a valve organization forming a separating wall between the outer and inner mixing chambers and including a 100 rotatably mounted valve body concentric to said annular valve and adjustably operable to regulate the quantum of the mixture which passes from the outer chamber to the inner chamber and a spider forming an 105 operative connection between said valve body and said annular valve to operate the latter from the former.

4. In a carbureter for internal combustion 110 engines, in combination, inner and outer concentric mixing chambers, an air passage communicating with the outer chamber, a fuel chamber, an absorbent distributing element submerged in the fuel in the fuel chamber, the wall separating said 115 fuel chamber and outer mixing chamber having openings between said chambers through which gasolene may be given off by the distributing element into said outer mixing chamber, and a valve organization 120 forming a separating wall between the outer and inner mixing chambers and comprising a rotatable cylindrical valve body having a base and having slots in its cylindrical portion, a stationary sleeve closely surround- 125 130

ing said valve body and having slots to register with the slots of said valve body, said base having air openings open to said air passage and an automatically acting spring held valve normally closing said air openings.

5. In a carbureter for internal combustion engines, in combination, first and second mixing chambers, a fuel chamber, 10 an absorbent distributing element submerged in the fuel in the fuel chamber, the wall separating the fuel chamber and the first mixing chamber having openings through which gasoline may be given off 15 by the distributing element into said first mixing chamber, an air passage communicating with the first mixing chamber and a valve organization forming a separating wall between the mixing chambers and including a movably mounted valve body adjustably operable to regulate the quantum 20 of the mixture which passes from the first to the second mixing chamber, said valve body having air openings open to said air 25 passage and an automatically acting spring-held valve normally closing said air openings.

6. In a carbureter for internal combustion engines, in combination, an air passage, 30 a fuel chamber, an annular wall separating said passage and said chamber and having an annular horizontal shoulder at its upper end, said shoulder having openings extending between its upper and lower faces, an 35 absorbent distributing element surrounding said annular wall within the fuel chamber and extending to said shoulder, concentric outer and inner mixing chambers above said air passage, the latter opening into the 40 outer mixing chamber, an annular valve rotatably mounted on said shoulder within the outer mixing chamber and controlling said openings, a valve organization forming a separating wall between said mixing 45 chambers and including a rotatable cylindrical valve body having a normally closed base and having slots in its cylindrical portion and a stationary sleeve closely surrounding said valve body and having slots 50 to register with the slots of said valve body, and an operative connection between said cylindrical valve body and said annular valve.

7. In a carbureter for internal combustion engines, in combination, an air passage, a fuel chamber, an annular wall separating said passage and said chamber and

having an annular horizontal shoulder at its upper end, said shoulder having openings extending between its upper and lower faces, an absorbent distributing element surrounding said annular wall within the fuel chamber and extending to said shoulder, concentric outer and inner mixing chambers above said air passage, the latter opening into the outer mixing chamber, an annular valve rotatably mounted on said shoulder within the outer mixing chamber and controlling said openings, a valve organization forming a separating wall between said mixing chambers and including a rotatable cylindrical valve body having a normally closed base and having slots in its cylindrical portion and a stationary sleeve closely surrounding said valve body and having slots to register with the slots of said valve body, and a spring spider operatively connecting said cylindrical valve body and said annular valve and acting to hold the latter on its seat.

8. In a carbureter for internal combustion engines, in combination, inner and outer concentric mixing chambers, an air passage communicating with the outer chamber, a fuel chamber, an absorbent distributing element submerged in the fuel in the fuel chamber, the wall separating said fuel chamber and outer mixing chamber having openings between said chambers through which gaseous vapor may be given off by the distributing element into said outer mixing chamber, a valve organization forming a separating wall between the outer and inner mixing chambers and comprising a rotatable cylindrical valve body 95 having a normally closed base and having slots in its cylindrical portion and a stationary sleeve closely surrounding said valve body and having slots to register with the slots of said valve body, a rotating fan mounted within said cylindrical valve body, said base having air openings open to said air passages, and an automatically acting spring-held valve normally closing said air openings and upon whose stem said fan is 100 mounted.

In testimony whereof I have hereunto set my hand in presence of two subscribing witnesses.

CHARLES DE LUKACSEVICS.
